Fig. 3

Fig. 5

A detailed technical drawing of a heating element assembly. The assembly includes a central heating coil (13) with a wavy pattern, mounted within a rectangular base plate (12). The base plate is secured to a larger, curved metal frame (22) using four bolts (21). A vertical support (19) is attached to the left side of the base plate. A flexible cable (8) is attached to the top of the heating coil. A label '14' is written above the assembly.

UNITED STATES PATENT OFFICE.

HENRY A. FRAMBURG, OF BERWYN, ILLINOIS.

ELECTRIC-LIGHTING FIXTURE.

1,321,023.

Specification of Letters Patent.

Patented Nov. 4, 1919.

Application filed March 21, 1918. Serial No. 223,699.

To all whom it may concern:

Be it known that I, HENRY A. FRAMBURG, a citizen of the United States, residing at Berwyn, in the county of Cook and State of Illinois, have invented a certain new and useful Improvement in Electric-Lighting Fixtures, of which the following is a full, clear, concise, and exact description, reference being had to the accompanying drawings, 10 forming a part of this specification.

My invention relates to electric lighting fixtures.

My improved fixture is intended for semi-direct or indirect lighting, either for indoor 15 or outdoor installations.

An important feature of my invention resides in the provision of improved means for adjusting the position of the lamp within the fixture. This is to permit the use of 20 lamps of different types and sizes within the fixture and still maintain the filament of the lamp at the proper focal point of the reflector. The adjustment, moreover, serves to accommodate the larger lamps to the limited space within the fixture.

I am aware that the broad idea of adjusting a lamp is old, but I have provided improved means and particular combinations of elements of a large measure, of utility 30 and have an adjusting mechanism which is simple, inexpensive and which has facility of operation.

I have provided the fixture with ventilating openings for permitting a circulation of 35 air therethrough. These openings are so arranged and screened that the fixture is substantially dust and insect proof.

The removable parts of the fixture, such as the globe and reflector, are preferably 40 supported by quickly releasable spring fingers, screw clamps and the like to facilitate removal and replacing of these parts for cleaning, adjusting and repairing of the fixture.

45 The general design and construction of the fixture is simple, durable and inexpensive of manufacture.

In the accompanying drawings I have 50 illustrated two particular embodiments of my invention.

Figure 1 is a side view, partly in section and partly in elevation, of one form of my improved fixture;

Fig. 2 is a section taken on the line 2—2 of 55 Fig. 1;

Fig. 3 is a side view, partly in elevation

and partly in section, of another form of my invention;

Fig. 4 is an enlarged detail section of 60 Fig. 1;

Fig. 5 is a section taken on the line 5—5 of Fig. 4;

Fig. 6 is a fragmentary plan view of the bridge shown in Fig. 3;

Fig. 7 is a detail sectional view of the 65 clamping arrangement shown in Fig. 3; and

Fig. 8 is a fragmentary view of the crown ring where one of the clamps is inserted.

Referring first to Fig. 1, the fixture is enclosed by a housing assuming the form of a 70 flared hood 1, preferably formed of sheet metal by spinning, which has co-extending from its upper end a bell-shaped portion 2. At its lower edge the hood 1 is formed with an annular shelf 3, upon which are secured 75 the screw-clamps 4—4 which support the globe 5. These clamps, of which there are three, have curved fingers 6 which engage under the annular flange 7 of the globe 5. A felt washer 10 is interposed between the 80 flange 7 and shelf 3.

In Figs. 4 and 5 I have illustrated in detail the construction of the clamps 4. A hollow barrel 8 is soldered or otherwise secured to the flat plate 9 which is in turn secured to 85 the shelf 3.

The front end of the barrel 8 is slotted horizontally for admission of the guiding tongue 11, integral with the finger 6. A thumb screw 12 threads into the front end of 90 the barrel 8, just above the tongue 11. This thumb screw is provided with spaced collars 13 between which engages the forked end 14 of the finger 6.

The thumb screw 12 is operable to release 95 or engage the clamping finger 6 with the annular flange 7 of the globe 5. The guiding tongue 11 is substantially the same width as the interior of the barrel 8 (Fig. 5).

The globe 5 has a flared portion 16 of 100 transparent crystal glass which is co-extensive with a semi-elliptical bowl 17 of translucent glass. The translucency is obtained by frosting or enameling either the outer or inner surface of the bowl 17 to afford a light diffusing surface for diffusing the brilliant direct rays from the lamp 18. This arrangement of the composite globe having transparent and translucent portions, is particularly intended for use with lamps of the 110 nitrogen filled type. The direct rays radiating from this style of lamp are excessively

brilliant, wherefore I have frosted the bowl 17 to diffuse those rays passing therethrough. The upwardly directed rays from the lamp 18 and those reflected up from the 5 interior of the bowl 17 strike the concave reflector 19 from whence they are reflected through the transparent portion 16 out into the room in the nature of indirect lighting.

The circular edge of the concave reflector 10 19 is rolled or curled inward, as shown at 20, and engaging over this edge to support the reflector are the spring fingers 21. There are preferably three of these fingers, which are riveted or otherwise secured upon the 15 inner walls of the hood 1. Two of the fingers 21 are of the configuration shown in Fig. 1, having their ends terminating in engagement with the rolled edge 20. The third finger 21' shown in Fig. 4, has a recurved end 22 which projects down into convenient position to be released by the hand of the attendant when it is desired to remove the reflector. Releasing of the finger 21' enables the reflector to be withdrawn from the 25 embrace of the other two fingers 21.

The reflector 19 has a central aperture 24 through which passes the neck 18' of the lamp 18. The plug end 25 screws into the porcelain socket 26 which has lateral ears 30 27-27 through which pass bolts 28-28 connecting with the bifurcated ends 29' of the stem 29. This stem is preferably of square section (Fig. 2) and I find it expedient to split the end as shown and thus make connection with the porcelain socket 26. This 35 socket may be of any preferred type.

The stem 29 extends up through a cap 31, concentric with an opening in the top of the bell shaped portion 2, and has a ring 40 or button 32 at its end which limits the descent of the stem 29 and in addition affords a convenient grasping portion for adjusting the stem vertically in the hood. A flanged bushing 33 threads into the interior of the 45 cap 31 and clamps the web of the bell portion 2 between its flange and the base of the cap 31.

One face of the square stem 29 is provided with a plurality of notches 34 spaced 50 to correspond with the different lengths of the lamps adaptable to the fixture. Intermediate notches for securing a finer adjustment may also be provided. A flat spring detent 35 which passes down alongside of the stem 29, with its end 36 turned under the bushing 33, is adapted to engage in these notches 34. The detent has a sharp nose 35' which engages in the notches 34 and has an extending finger portion 37 which 55 may be operated to raise the detent out of the notches. The operation of the adjustment feature will be obvious from the foregoing description.

In order to secure maximum lighting efficiency it is important to support the lamp

within the globe so that the illuminating element will be maintained substantially equidistant from the surrounding surfaces of the globe. This condition may be readily obtained by having the manipulating parts 70 of the adjustment in this form external of the hood 1. This allows adjustment of the lamp after the reflector and globe have been completely assembled in the fixture, thus the proper positioning of the lamp filament 75 relative to the reflector surface may be obtained with the fixture completely assembled by noting the reflection and distribution of the light rays. If the rod 29 drops down it cannot break the lamp because of 80 the enlarged ring or button 32 at its upper end.

A shoulder 39 is formed at the juncture of the main hood 1 and the bell-shaped portion 2. An annular ring 41 of stiff gauze 85 or perforated sheet metal seats on this shoulder and supports a flaring petticoat 42 concentric with the bell portion 2. This petticoat shields the ventilating openings 43, cut in the walls of the portion 2. The 90 petticoat 42 prevents the entrance of snow and rain into these openings and by the provision of the gauze 41 filters any air tending to rise into these openings.

It will be noted that the rolled edge 20 95 of the reflector 19 is spaced away from the vertical wall of the hood 1. The air heated at the bulb portion of the lamp ascends along the surface of the reflector 19 and passes up around the edge of the reflector 100 into the flaring part of the hood 1, from whence it rises and passes out through the ventilating openings 43.

The stem 29 is hollow, as shown in Fig. 2, and passing down through this circular bore therein is the duplex conductor 44. This conductor affords electrical connection 105 between the outlet box in the ceiling or overhead support and the socket 26.

An eye loop 45, integral with the cap 31, 110 extends up and over the top of the stem 29, where it is linked by the supporting chain 46.

The form of fixture just described is the preferred form for outdoor installations. 115

The embodiment illustrated in Fig. 3 is particularly intended for interior use, and is adapted to be fastened directly to the ceiling. The housing of this form of fixture assumes the shape of an ornamental crown ring 48, of stamped sheet metal with a bead 68 formed at the lower end. A bridge 49 of flat bar iron extends diametrically across the inside of the ring 48 and supports the latter from the ceiling. The vertical ends 49' of the bridge 49 are attached to the ring 48 by screws 50 passing through the ring 48. The clamp 4' is supported within the lamp upon an annular shelf member composed of the split ring 69 which is snapped 120 125 130

into the bead 68. The thumb screw 12 passes through the opening 70 in the ring 48 and the guiding tongue 11 which is formed integral with the finger 6, passes 5 through the slot 71 below the opening 70.

The reflector 19' has an inwardly rolled edge 20' which rests upon spring fingers 52, one of which has a recurved end, similar to the end 22 of Fig. 4.

10 The socket 26' is suspended from the bridge 49 by screws 53 which pass freely through holes in the ears 27' and thread into the bridge 49. A plurality of short spacing sleeves 54 are disposed about the 15 screws 53.

15 The vertical adjustment of the socket 26' is obtained by changing the relative positions of the sleeves 54 above and below the ears 27'. Thus, to raise the socket in accommodating the fixture to a larger size 20 lamp, all of the sleeves would be disposed on the screw shanks below the ears 27', and for lowering the socket, in the case of a 25 smaller size lamp, all of the sleeves would be disposed above the ears 27'.

20 It will thus be seen that maximum lighting efficiency may be obtained with this form of fixture as has been described with respect to the form illustrated in Fig. 1 of the drawings.

25 The bridge 49 is fastened by means of a stud bolt 61 and the lock nuts 62 and 63. The lateral ears 64 and 65 of the stud bolt 61 are fastened to the top of the outlet box 35 55 by screws 66. It will be evident that the bridge can be suspended from other fastening means, such as a pipe nipple or the like. The bridge 49 is provided with the slots 58—58 through which pass screws 59 40 engaging in the ceiling or in the interior flange 67 of the outlet box 55, thus affording an additional supporting connection for the bridge. The slots 58 permit different locations of the screws 59, for insuring engagement of the screws in a joist or beam.

45 The conductor 56 extends down from the

outlet box 55 to the socket 26'. The crown ring 48 has cut therethrough adjacent its lower edge a plurality of ventilating openings 60 suitably screened as shown.

50

I do not intend to be limited to the particular details herein shown and described except as they are defined in the appended claims.

I claim:

1. In a clamp for lighting fixtures, a 55 clamping member, screw means for moving said member into clamping engagement, and guide means secured to said member and operating in a guideway for guiding the motion of said member.

2. In a clamp for lighting fixtures, a 60 clamping member comprising a clamping finger, a guiding tongue and a fork portion, screw means for operating said clamp, said 65 screw means having collars engaging with said forked portion, said guiding tongue moving in a guideway to guide said clamping finger.

3. In an electric lighting fixture, a hood, 70 a reflector within the hood, a globe having a curved, closed lower end and suspended from the hood and forming therewith a substantially closed lamp casing, a socket within said casing above said reflector, a lamp carried by the socket projecting through the reflector and extending within the globe, and means carried by the casing and above said reflector for adjusting said lamp from and toward the globe.

75

4. In a clamp for lighting fixtures for supporting a shade, a clamping member having a shade supporting arm, a screw upon which said member is rotatably mounted, and guide means secured to said member 80 and operating in a guide way for guiding said arm in its out and in movement.

45 In witness whereof, I hereunto subscribe my name this 27th day of February, A. D. 1918.

HENRY A. FRAMBURG.
